SWEET-FEED MIXER

Tom H. Riza, Cleburne, Tex.

Application February 24, 1938, Serial No. 192,420

3 Claims. (Cl. 259—9)

This invention relates to an apparatus for mixing feed.

It is an aim of this invention to provide an improved apparatus for mixing cereals of various forms with molasses or other syrups to provide a fodder containing desired portions of different ingredients, and which may be operated without the use of heat even at very low temperatures.

10 A further object of the invention is to provide a feed mixer having means to supply the molasses to the cereal as it is passing into the mixing chamber, in the form of a fine spray to be thoroughly mixed, as a result, more readily when it reaches the agitating means of the mixing chamber.

15 A further object of the invention is to provide means to maintain the mixed feed in the mixing chamber until a certain pressure has been reached thereby insuring thorough distribution of the 20 molasses even under very low temperatures.

Still a further object of the invention is to provide means whereby the molasses will not drain into the agitator chamber when the device is not in use to leave a residue which will prevent the 25 proper operation of the device thereafter.

Other objects and advantages of the invention will hereinafter become more fully apparent from the following description of the drawings which illustrate a preferred form of the invention, and 30 wherein:

Figure 1 is a side elevational view of the apparatus in its entirety.

Figure 2 is a vertical sectional view taken on the line 2—2 of Figure 1.

35 Figure 3 is a vertical sectional view taken on the line 3—3 of Figure 1.

Figure 4 is a longitudinal central vertical sectional view taken on the line 4—4 of Figure 2.

40 Figure 5 is a transverse vertical sectional view taken on the line 5—5 of Figure 1.

Figure 6 is a fragmentary enlarged front elevational view of a portion of the manifold molasses pipe.

45 Figure 7 is a fragmentary longitudinal vertical sectional view of a slightly modified form of the invention, and

Figure 8 is a transverse vertical sectional view taken on the line 8—8 of Figure 7.

50 Referring more particularly to the drawings wherein like reference characters designate like or corresponding parts throughout the different views, 10 designates generally the framework in its entirety, on which the mixing apparatus comprising this invention is supported.

55 The feed mixer 11 comprises a mixing chamber

12, which is cylindrical in form and which is provided with a hopper or inlet passage 13, projecting upwardly from adjacent one end thereof, and a depending outlet passage 14 disposed adjacent the opposite end thereof. A shaft 15 extends longitudinally of and centrally through the chamber 12, and is provided with reduced ends 16 which are journaled in the ends 17 of the chamber 12. The screw blade agitators and conveyors 18 and 19 are mounted on shaft 15 and are adapted to be 10 rotated thereby in the chamber 12 to mix the feed and to convey it therethrough. A pulley 20 is mounted on one end 16 and is connected by a belt 21 with a pulley 22 mounted on shaft 23 which is driven by an electric motor 24 to drive shaft 15 15 and the blades 18 and 19.

A pair of flap valves 25 and 26 are pivotally mounted in the outlet 14 in a hood 27 respectively, to normally close the outlet end of chamber 12. The valves 25 and 26 are provided with the arcuately shaped recesses 28 through which the shaft 15 extends when the valves are in a closed position, as seen in Figure 3. Valves 25 and 26 are pivotally mounted on the levers 29 and 30, respectively, which have their angularly bent ends 25 connected to the contractile springs 31 and 32 which are each connected at their opposite ends to parts of the frame 10 to normally retain the valves in a closed position.

A pipe line 32 leading from a source of syrup 30 or molasses supply, not shown, includes an angularly disposed portion 33 in which is mounted a pump 34. Section 33 connects with the section 35 of the pipe line 32 which extends upwardly and inwardly to terminate adjacent one side of the 35 hopper 13. Section 35 is provided with a plurality of spaced, angular shaped nozzles, projecting upwardly from the top of the pipe 35, with their open ends extending into hopper 13. The open ends of the nozzles 36, as seen in Figure 6, 40 are crimped at their bottom to form the vertically disposed partition 38 dividing each nozzle into two sections. An angular section 39 of pipe, connects with the opposite end of the section 33 and with the inlet end of the pipe line 32 and 45 with the section 35, to form a return pipe. Mounted in the adjacent ends of the pipes 35 and 39 are the return valves 40 and 41, respectively, which are connected to the levers 42 and 43, respectively. Levers 42 and 43 are connected by 50 the link 43 so that the manual movement of lever 42 and valve 40 in one direction will move lever 43 and valve 41 in the opposite direction. Lever 42 is provided with the arrow tipped end 44 mounted to move in front of the segmental cali- 55

brated dial face 45 which is suitably marked to indicate the various positions of the valves 40 and 41. Mounted in pipe 35 above valve 40 is a pressure gauge 46 to indicate the pressure in pipe 35.

5 Pump 34 mounted in the pipe 33 is connected to one end of a drive shaft 47 which is journaled in the upright bearing 48. A pulley 49 is connected to the opposite end of shaft 47 and to a pulley 50 keyed to shaft 15 by a belt 51 which is 10 trained over the pulleys 49 and 50. Pump 34 is thus driven by the electric motor 24 simultaneously with the shaft 15. The outlet 14, terminates at its outlet end in the two passages 52 having a flap valve 53 mounted therebetween, in the passage 14 and operable by means of a lever 54 which is manually swung from side to side to successively close one of the passages 52 and open the other. A hook 55 is secured to each of the passages 52 to support a feed bag into which the 15 mixed feed is dispensed as will hereinafter be described. Mounted on shaft 15 and above outlet 14 is an impeller 56 adapted to be revolved by the shaft 15 to impel the mixed feed into the outlet 14 after it has passed through the valves 25, 26.

The frame 10 by which the apparatus 11 is supported includes the bearings 57, as seen in Figure 4, in which the ends 16 of the shaft 15 are journaled.

30 In Figures 7 and 8 a slightly modified form of the invention is shown, wherein the valve 58 replaces the valve 26, and is slidably mounted in chamber 12 and hood 27. The flap valve 25 is pivotally mounted on the shaft 59 to the opposite ends of which are keyed the cranks 60 which have their free ends connected by the links 61 to a rod 62 connected to the upper end of the sliding valve 58, so that when valve 25 is swung to an open position by the pressure of the feed in chamber 12 cranks 60 will swing upwardly to raise valve 58 to its open position.

From the foregoing it will be seen that motor 24 will drive shaft 23 to drive pulley 21 and the shaft 15 to revolve the agitating and conveying blades 18 and 19 in chamber 12. Blades 18 and 19 are arranged in spaced relationship to each other, with blade 18 directly beneath hopper 13 to receive the feed to be mixed as it enters the chamber 12. As heretofore explained the syrup, 45 preferably in the form of molasses will pass through pipe line 32 up through pipe 33 into which it will be drawn and from which it will be driven by pump 34 operated as heretofore described, to force the molasses through pipe 35 and through the jets 36 which will throw a fine spray of molasses across the hopper 13 to mix with the forage as it is emptied into the hopper and before it enters the chamber 12. The forage and molasses will be mixed and conveyed by the 50 blades 18 and 19 in and through chamber 12 until it reaches the valves 25 and 26 which will prevent its further movement until it is thoroughly mixed and until the pressure in the chamber 12 reaches a predetermined point necessary to 55 actuate levers 29 and 30 against the resistance of springs 31 and 32 to open valves 25 and 26. When

valves 25 and 26 are partially opened by the pressure of the feed, the feed will pass therethrough and be engaged by the impeller 56 which will drive it into outlet 14 to be dispensed through one of the outlets 52 to which is attached a bag by means of hooks 55 to receive the mixed feed. The valve 53 will be operated to successively open the outlets 52 to fill the empty bags which are connected to the hooks 55, in the well known manner. It is desirable to vary the amount of molasses used, and this may be readily accomplished by adjustment of lever 42 to adjust the opening of valve 40 to any desired pressure as indicated by the gauge 46. As valve 40 is closed valve 41 will be opened, as heretofore described, to permit the syrup to pass through pipe 39 to prevent back pressure on the pump 34. When the device is not in operation valves 40 and 41 may be left partly open to permit the molasses to drain out of nozzles 36 and pipe 35 so as not to drip into chamber 12 where it can harden into a sticky mass to prevent proper operation of the device and uniform mixing of the ingredients.

Various modifications and changes in the construction and operation and arrangement of the apparatus may obviously be made and are contemplated, and the right is expressly reserved to make such changes and modifications as fall within the spirit and scope of the invention as hereinafter defined by the appended claims.

I claim as my invention:

1. In a device of the class described, a mixing chamber adapted to contain forage and molasses, agitating and conveying means mounted in said chamber, a plurality of nozzles connected to a molasses conduit and projecting upwardly therefrom and adapted to mix finely sprayed molasses with the forage as it passes into said chamber, a pump adapted to convey the molasses to said nozzles under pressure, and a plurality of connected valves mounted in said conduit and controlled by a common lever to vary the pressure of the molasses and to permit the molasses to drain back through said conduit when said mixer is not in operation.

2. A device as in claim 1, said conduit being provided with a by-pass adjacent its outlet end, controlled by said valves, said valves being moved in opposite directions thereby to open one as the other is closed to prevent a back pressure on said pump and for draining off the molasses through said by-pass when the pump is not in operation.

3. In a sweet feed mixer, a mixing chamber having an upwardly extending inlet passage, a plurality of upwardly and inwardly extending nozzles opening into said passage, a conduit for supplying molasses to said nozzles, a pump mounted in said conduit, said conduit including a by-pass extending around said pump, and a plurality of connected valves mounted in said conduit and operated by a common lever to control the pressure of the molasses supplied to said nozzles and to provide means whereby the molasses is drained back through said by-pass when the pump is not in operation.

TOM H. RIZA.
